UNITED STATES PATENT OFFICE.

LOUIS ALBERT SAMSTAG, OF NEW YORK, N. Y.

HAIR-NET-DISPLAY DEVICE.

1,376,782.

Specification of Letters Patent.

Patented May 3, 1921.

Application filed December 31, 1920. Serial No. 434,333.

To all whom it may concern:

Be it known that I, LOUIS ALBERT SAMSTAG, a citizen of the United States, and resident of New York city, in the county of New York and State of New York, have invented certain new and useful Improvements in Hair-Net-Display Devices, of which the following is a specification.

My invention relates to advertising devices, and is more particularly directed to an improved display device for advertising and demonstrating hair nets.

A principal object of my invention is to produce an advertising device which will utilize the principle of direct comparison and demonstration to impress upon observers the advantages of using hair nets. In general I accomplish this object by employing two lay figures of women in close proximity to each other, each having hair or a material resembling hair suitably mounted thereon. The hair on one figure, however, is neatly confined, while that upon the other figure is disheveled and free to blow about. These figures are so arranged and constructed that when a strong current of air, as from an electric fan, is directed against the disheveled hair of one figure, preferably in the general direction of the other figure, the hair will be blown about, producing the untidy appearance which it is the purpose of hair nets to prevent. At the same time the hair of the other figure, which apparently is subjected to the same current of air, retains its neat and even appearance. With this arrangement the actual appearance of the two figures, one with hair blowing about and the other with hair neat and unaffected by the breeze, presents a vivid comparison which will obviously constitute a most effective sales argument.

A further object is to produce a device of the type indicated which will tend to attract and hold attention by means of its unusual nature and the employment of a moving element calculated to catch the eye.

Another object is the development of a device of this type which is of such a nature that it can be readily adapted for the wide variety of conditions in which such advertising displays and demonstrations are customarily employed, and which will conform to practical requirements, such as reasonable ease of production, simplicity and certainty of operation, convenience in shipping and installing, and other like characteristics.

I have illustrated in the drawings one of

the various forms in which my invention may be embodied. In the example shown, Figure 1 is a front elevation, and Fig. 2 is a top plan view, somewhat diagrammatic in its nature.

My invention is particularly adapted to be embodied in advertising displays of the type made of cardboard and adapted to be set up by a merchant in a suitable place, such as his show window or on a counter. In the specific arrangement which is illustrated, the cardboard display includes a front 10 which is in the general form of a frame, and upon which the trade mark, the manufacturer's name, and other matter may be printed. Some distance behind the front 10 is mounted a background sheet 11, which may be supported in any desired way, as by webs 12 connecting it with the front 10. The lay figures 13 and 14 are cut from a sheet of cardboard 15 located intermediate the front and back, a convenient arrangement being to bend the ends of the cardboard 15 forwardly as at 16 and attach them to the frame-like front 10 at a point invisible to the observer, the sheet 15 carrying at each side of the figures, if desired, suitable portions of scenery such as trees 17 and shrubbery 18 in the example illustrated, which blend with the background scene, thereby providing a highly pleasing and realistic appearance.

I mount on figure 13 a suitable material 19 which either is hair or some material which closely resembles hair. On this figure the hair is arranged neatly and held in position, either by the method of attaching the hair, or by means of part or all of a hair net. It is noted however, that the net need not necessarily be actually used, as many of such nets are supposed to be invisible, and it is not desirable to have them too prominent in the display. The hair or hair-like material 20, similarly attached to the other figure 14, is somewhat long and disheveled, and has loose ends of material of substantial length which fall across the face of the figure and are free to blow about in a current of air.

Such current may be produced in various ways and directed against the hair. One convenient arrangement for this purpose is illustrated in Fig. 2, in which an electric fan 21 is mounted at one side of the device in position to propel a strong current of air against the hair 20, blowing it across the face of the figure 14 and in the general di-

rection of the figure 13, whose hair 19 is so mounted that it will remain undisturbed by the current. Obviously however, a variety of other arrangements for propelling a current of air against hair 20 may be substituted for that shown.

It will be apparent that the specific construction shown is purely illustrative, the number of variations possible being limited 10 only by the ingenuity of the designer. For instance, it will be apparent that figures 13 and 14 may be much more elementary in type, and may be employed free from the background and front frame. Figures 13 15 and 14 are so arranged that only such hair is visible as would ordinarily appear beneath a hat; but obviously, while this arrangement is very convenient for the type of advertising display shown, my invention is not 20 limited thereto. Nor is it limited to stationary figures, nor restricted to merely a pair of figures, since obviously these features can be varied without departing from my fundamental idea. This idea is to employ 25 two figures one with confined hair and the other with disheveled hair, and to direct an air current across the figures so that the disheveled hair will blow about, the figures being so arranged that a prospective customer will necessarily observe both simultaneously, to impress the advantage of hair nets by direct comparison between the appearance of netted and unconfined hair. I believe that I am the first to devise this 30 arrangement and method of demonstrating the advantage of hair nets; and do not consider my invention to be restricted to any particular form or method of embodying the invention.

40 It will be apparent however that the particular device shown is desirable from a practical standpoint, as it may readily be shipped in flat form and can be easily set up in a store window to provide a large and 45 effective display of the type calculated to attract the casual passer-by.

I have referred in the specification and claims to lay figures; but while I prefer to use representations of women, many types 50 of figures of this kind being well known, it will be apparent that the hair may be mounted upon any suitable support for the purpose of my invention; and I do not consider my invention as restricted to the particular type of lay figure shown herein.

While I have indicated certain variations in construction and various embodiments of my invention, it will be apparent that a great many other changes and forms may be used 60 within the scope of the invention, as particularly set forth in the following claims.

I claim:

1. Apparatus for demonstrating the advantages of the use of hair nets by comparison, including a pair of lay figures in

juxtaposition to each other adapted to be simultaneously observed, a material having the appearance of hair mounted on one figure and free to blow about in a current of air, material having the appearance of hair 70 mounted on the other figure and confined to prevent it from blowing about in said current, the construction being such that when a current of air is directed across the figures, the hair-like material on one figure will blow 75 about while that on the other will be substantially unaffected.

2. Apparatus for demonstrating the advantages of the use of hair nets by comparison, including a pair of lay figures in 80 juxtaposition to each other adapted to be simultaneously observed, a material having the appearance of hair mounted on one figure and free to blow about in a current of air, material having the appearance of hair 85 mounted on the other figure and confined to prevent it from blowing about in said current, and means for directing a current of air against the first mentioned hair-like material, the construction being such that when a current of air is directed across the figures the hair-like material on one figure will blow about while that on the other will 90 be substantially unaffected.

3. Apparatus for demonstrating the advantages of the use of hair nets by comparison, including a pair of lay figures in 95 juxtaposition to each other adapted to be simultaneously observed, said figures being arranged in transverse alinement, material 100 having the appearance of hair mounted on one figure and free to blow about in a current of air, material having the appearance of hair mounted on the other figure and confined to prevent it from playing about in said current, and means in alinement with 105 said figures for producing a current of air and located so as to blow the first mentioned hair-like material carried by one lay figure 110 in the direction of the other lay figure.

4. Apparatus for demonstrating the advantages of the use of hair nets by comparison, including a pair of lay figures formed of sheet material and located substantially in alinement and in juxtaposition to each other so that both may be simultaneously observed, material having the appearance of hair mounted on the front of one figure and free to blow about in a current of air, similar material mounted on the front of the other figure and confined to prevent it from blowing about in said current of air, and means in alinement with said figures for directing a current of air against 115 said free hair-like material to blow it toward 120 the other figure.

Signed at New York city, in the county of New York and State of New York, this 20th day of December, A. D. 1920.

LOUIS ALBERT SAMSTAG.
